UNITED STATES PATENT OFFICE.

CHARLES C. MENGEI, OF LOUISVILLE, KENTUCKY, ASSIGNOR TO MENGEI BOX COMPANY, OF LOUISVILLE, KENTUCKY, A CORPORATION OF NEW JERSEY.

KNOCKDOWN BOX.

No. 927,262.

Specification of Letters Patent.

Patented July 6, 1909.

Application filed August 31, 1908. Serial No. 450,992.

To all whom it may concern:

Be it known that I, CHARLES C. MENGEI, a citizen of the United States, residing at Louisville, in the county of Jefferson and State of Kentucky, have invented certain new and useful Improvements in Knockdown Boxes, of which the following is a specification.

My present invention pertains to improvements in knock-down boxes, the construction 10 and advantages of which will be hereinafter set forth, reference being had to the annexed drawings, wherein:

Figure 1 is a perspective view of the box or crate in its knocked-down or unfolded condition; Fig. 2 a sectional perspective view of the closed box; Fig. 3 a longitudinal sectional view of the box, showing the battens or cleats of the heads turned inwardly (the reverse of the position shown in Fig. 2) to 20 produce a shorter space within the box; the figure also illustrating the sides, bottom and top as provided with grooves intermediate the ends to receive a partition (or partitions) to subdivide the box; and Fig. 4 a 25 detail sectional view, illustrating a slight modification.

The main object of the invention is to produce a simple and efficient knock-down box, preferably formed of compound or veneer lumber, the construction being such that by 30 merely positioning the heads with different sides thereof innermost the effective interior length of the box may be readily altered.

A further object of the invention is to 35 provide means, such as intermediate partitions, by which the interior space of the box may be subdivided, the end spaces or subdivisions being capable of change in size by shifting the heads face for face.

40 A still further object of the invention is to so form the edges of the sides (by which term I mean also to include the top and bottom) that when the structure is folded into its closed position the edges will have a fair bearing on each other, forming a tight joint, 45 with the sides mutually sustaining each other.

Another object of the invention is to provide 50 a simple and effective wire hinge connection between the various sides, while a still further object it to provide means for protecting the openings or holes formed adjacent to the edges of two of the sides through which the fastening and sealing 55 wires are passed.

With these and other objects in view, a detail description of the invention will be given.

The sides (which term generically includes the top and bottom) of the box are designated by 1, 2, 3 and 4, and are preferably formed of compound or veneered lumber with the grain of the central ply running at right angles to that of the other layers. The edges 5 of each side are beveled at an 65 angle of 45° so that when the box is folded or squared, the beveled faces have a fair bearing upon each other, as clearly indicated in Fig. 2.

The various sides are connected by suitable 70 hinges, preferably such as shown in detail in Figs. 1 and 2. Each hinge comprises two sections, hooked or interlooped together. Each loop 6 is formed of a single piece of wire, doubled upon itself, the ends of 75 the wire being driven or passed through the side of the box from the outer surface thereof, the body being flattened against the inner face of the side, while the ends are turned and driven into said inner face. This securely fastens the hinges in place and prevents the loops from being withdrawn or torn out by any unusual strain to which the package 80 may be subjected in transit or in handling.

The loops proper lie almost flat against the outer faces of the sides and are made of such length that when the box is folded, the beveled edges of the sides will come close together and no play will take place between 90 them. This construction avoids the necessity of the use of screws, rivets, nails or other fastening devices, which are employed with the usual form of hinge.

Each side, adjacent to each end, is formed 95 with a groove or channel 7. Said grooves, when the box is folded, are adapted to receive the edges of the heads 8 and 9, as clearly shown in Fig. 2. Each head is preferably formed of compound lumber and has secured to it, at a distance from its edge approximately equal to the depth of the groove 100 7, battens or cleats 10 which serve to stiffen the head and likewise, when the box is folded, to bear against the inner faces of the 105 sides and thereby sustain the sides.

By the employment of battens or cleats the interior length of the box may be varied, as by shifting the heads to bring the battens innermost, as shown in Fig. 3, the effective 110

- length is decreased by the thickness of the battens. By reversing one head alone, the shortening will be decreased one half. Assuming, for instance, that the cleats are 5 three-fourths of an inch thick, it will be seen that the effective interior length may be shortened three-fourths of an inch if one head be reversed, or one and one-half inches by reversing both heads. By providing various heads, having cleats of different thickness, the interior of the packages may be changed to suit the occasion, it being often-times desirable to ship small articles without changing the outer dimensions of the package. 10 Again, the sides may be provided with grooves or channels 11, Fig. 3, located intermediate the ends, for the reception of partitions 12, by which the box may be subdivided.
- 20 Inasmuch as the boxes are shipped back to the packer, the employment of heads with various-sized cleats would be a matter of investment, and not an item of constantly-recurring expense and special work, as would 25 be the case were it attempted to build a special box for each occasion when one slightly shorter than the stock size was required. It is readily conceivable that instead of securing battens or cleats to each head to form filling members, the cleat might be formed as a single piece secured to the head, as at 10^a, at the left-hand end of Fig. 3. The cleats are, however, preferred for various reasons. Should it become necessary to strengthen 30 the structure when partitions are employed, an extra bottom piece 13, grooved to receive one edge of the partition, may be secured in the box.
- It will be readily appreciated by those 40 skilled in the art that it is not essential that all four sides of the box should be provided with the supplemental grooves 11 to receive the partitions 12, it being necessary only to form grooves in two oppositely-disposed sides.
- Any suitable means may be employed for 45 securing the package in its closed position, but I prefer to form openings 14 in the free edges of the sides 1 and 4, and to pass wires therethrough, which wires will be twisted and, if necessary, provided with a seal 16. To prevent the wire from being torn out, accidentally or otherwise, the openings, one or all, may be provided with eyelets 17.
- 50 55 The package herein described is light and yet stable; it is easily assembled in the course of manufacture and as readily brought from

its knock-down shape to a box-like form and securely fastened.

Having thus described my invention, what I claim is:

1. In a knock-down box, the combination of a series of sides; a series of hinges securing the sides together, each hinge comprising a pair of interlooped loops, the ends of each loop being passed inwardly through a box-side and secured thereto; a pair of heads; and means for securing the normally-free edges of the sides together when the parts are assembled. 70

2. In a knock-down box, the combination of a series of sides, the opposite edges of which are beveled; a series of hinges securing the sides together, each hinge comprising a pair of interlooped loops, the end of each 75 loop being passed inwardly through a box-side and then bent over and driven inwardly into the inner face of the side; a pair of heads; and means for securing the normally-free edges of the sides together when the parts 80 are assembled.

3. In a knock-down box, the combination of a plurality of sides; a series of wire hinges secured to the same and connecting them together, each hinge comprising two interlooped loops; the loop-shaped portion lying without the sides, while the ends of the wire pass through the side and are bent over and driven into the inner face of the sides; 85 heads; and means for securing the parts together when brought to their assembled position. 90

4. In a knock-down box, the combination of a series of sides hinged together, the proximate edges of the sides being beveled and each side having a groove formed therein adjacent to each end and likewise a plurality of grooves intermediate said end grooves; a pair of reversible heads, each head having a filling member secured to one face thereof; 100 a partition adapted to be fitted into one or another of the series of intermediate grooves, whereby compartments of various lengths may be formed within the box by the shifting of the heads or of the partition or the 105 shifting of both; and means for securing the parts together when assembled.

In testimony whereof I have signed my name to this specification in the presence of two subscribing witnesses.

CHARLES C. MENGEL.
